Primary Examiner — Karen S Acker*Assistant Examiner* — Wendy L Arminio(74) *Attorney, Agent, or Firm* — Thomas C. Feix**(57) CLAIM**

The ornamental design for a film with pattern, as shown and described.

DESCRIPTION

The sole FIGURE is a top plan view of a film with pattern showing our new design.

The dot-dash-dot broken lines surrounding the FIGURE depict the boundaries of the claim and form no part thereof.

1 Claim, 1 Drawing Sheet(56)
